UNITED STATES PATENT OFFICE.

SAMUEL HARRIS, OF CLEVELAND, OHIO, ASSIGNOR TO THE STEEL MOTOR COMPANY, OF SAME PLACE.

CONTACT-FINGER FOR ELECTRIC CONTROLLERS.

SPECIFICATION forming part of Letters Patent No. 536,803, dated April 2, 1895.

Application filed December 5, 1894. Serial No. 530,889. (No model.)

To all whom it may concern:

Be it known that I, SAMUEL HARRIS, a citizen of the United States, residing at Cleveland, in the county of Cuyahoga and State of Ohio, have invented certain new and useful Improvements in Contact-Fingers for Electric Controllers; and I do hereby declare the following to be a full, clear, and exact description of the invention, such as will enable others skilled in the art to which it appertains to make and use the same.

My invention relates to improvements in the contact fingers of electric controllers. Its object is to increase the efficiency and adaptability of the apparatus; and it consists in the novel construction, arrangement and combination of the parts to effect such object, as hereinafter fully described and specifically pointed out in the claims.

20 In the drawings Figure 1 represents in side view a contact finger embodying my invention, shown in engagement with one of the connecting disks of the roller of a street car controller. Fig. 2 represents the same in plan view.

A represents the connecting disk of insulating material; a, the contact strip embedded in its periphery.

B is an insulating disk interposed between 30 each of the disks A, parts of two of which are shown in Fig. 2.

C is the contact finger, composed of the shoe or bearing piece c attached to an endless spring c², preferably of oval or elliptic shape 35 and of flat metal, which is attached at its opposite side to the carrying piece c³, whereby the finger is secured to the bar D', in position to bear against the disk A, so as to effect the electrical connection of the circuit in the 40 usual way when the roller is appropriately turned by its handle.

It is well understood that the bearing between the bearing surface of the finger and the disk must be as complete as possible in 45 order to decrease the resistance and avoid the heating of the roller and the inevitable burning of the contacts or other parts. For this reason the contact fingers are usually provided with springs to insure their firm contact with the disk, and various forms of coiled and flat springs arranged in various ways have been adopted in the effort to se-

cure this very desirable end. There is, however, a tendency to an unequal wear on the shoe or contact piece of the finger, which 55 renders it essential to the best results that it should have practically universal play, yet a rigidity greater than could be obtained by any joint, which would also introduce resistance and be objectionable on that account. 60

I accomplish the results aimed at by the construction above described, as the elliptical spring yields readily to pressure in any direction and also transversely, so that the shoe c has sufficient freedom of motion both laterally and longitudinally and yet is kept to a firm bearing not only throughout its length but also throughout its width. This result cannot be obtained with coiled or flat springs, as the latter do not insure perfect lengthwise 70 contact of the shoe, and neither affords perfect compensation for lateral wear.

The finger is attached to bar D' by means of a connecting piece D to which it is secured by screws e e, and in case of burning or 75 greater wearing of the shoe c at one end than the other, the entire finger may be reversed by removing the screws e e and replacing the finger inverted, so that thereby the life of the finger may be prolonged. 80

What I claim as my invention, and desire to secure by Letters Patent, is—

1. A contact finger for electric controllers having the contact shoe rigidly affixed to an endless spring which is free to flex in any direction and is rigidly affixed to a carrying piece, substantially as described. 85

2. A controller finger for electric controllers having the contact shoe rigidly affixed to an endless spring of flat metal which is free to 90 flex in any direction and is rigidly affixed to a carrying piece, substantially as described.

3. A contact finger for electric controllers having the contact-shoe rigidly affixed to an endless elliptical spring which is free to flex 95 in any direction and to which is rigidly affixed a carrying piece, substantially as described.

4. A controller finger for electric controllers having the contact-shoe rigidly affixed to an 100 endless elliptical spring of flat metal which is free to flex in any direction and to which is rigidly affixed a carrying-piece, substantially as described.

5. A contact finger for electric controllers having the contact-shoe rigidly affixed to the long side of an elliptical spring which is free to flex in any direction and whose free portions are without joints, and to the opposite side of which spring is rigidly affixed a carrying piece, substantially as described.
6. A contact finger for electric controllers having the contact-shoe rigidly affixed to the long side of a flat elliptical spring which is free to flex in any direction and whose free portions are without joints, and to the opposite side of which spring is rigidly affixed a carrying piece, substantially as described.
- 10 7. A reversible contact finger for electric controllers having the contact-shoe rigidly affixed to an endless spring to which is rigidly affixed a reversible carrying piece, substantially as described.
- 15 8. A reversible contact-finger for electric

controllers having the contact shoe rigidly affixed to an endless spring of flat metal to the opposite side of which is rigidly affixed a reversible contact-piece, substantially as described.

25 9. In a contact-finger for electric controllers the combination of the reversible carrying piece having similar sides, the flat elliptical spring rigidly affixed thereto by one of its long sides and having its free portions without joints, and the contact-shoe rigidly affixed to the opposite side of the spring and having both ends alike, substantially as described.

30 In testimony whereof I hereto affix my signature in presence of two witnesses.

SAMUEL HARRIS.
